STEPHAN HASENBÜHLER, OF PHILADELPHIA, PENNSYLVANIA, ASSIGNOR
TO H. A. OESTERLE AND COMPANY, OF SAME PLACE.

Design No. 2,691, dated July 2, 1867.

DESIGN FOR BLIND-BINDING.

The Schedule referred to in these Letters Patent and making part of the same.

TO ALL WHOM IT MAY CONCERN:

Be it known that I, S. HASENBÜHLER, of Philadelphia, county of Philadelphia, State of Pennsylvania, have invented or produced a new and original Design for a Blind-Binding; and I do hereby declare that the accompanying drawing, and the following explanation thereof, form a full, clear, and exact description of the said design.

In the accompanying drawing the figure represents a section of blind-binding, at each side of which is an ornamental edge, a.

In the centre of the fabric is a number of ornamental figures, A and B, of the character shown in the drawing, the figures A alternating with the figures B.

I claim the design for a blind-binding, substantially as shown in and by the accompanying drawing.

In testimony whereof I have signed my name to this specification in the presence of two subscribing witnesses.

STEPHAN HASENBÜHLER.
